UNITED STATES PATENT OFFICE

JENS N. OKSENHOLT AND JAMES A. COLEMAN, OF JENA, LOUISIANA

DRILLING AND CORING TOOL

Application filed September 28, 1926. Serial No. 138,306.

This invention relates to an improved drilling and coring tool.

The object of the invention is to provide a drilling and coring tool which will form and retain a sample of the formation and which is so constructed and organized that the core may be readily taken from the tool.

Another object resides in the provision of a device of this character wherein provision is made for effective drilling and coring and for the circulation of water or other fluid during the drilling and coring operation.

Other objects and advantages reside in certain novel features of the construction, arrangement and combination of parts which will be hereinafter more fully described and particularly pointed out in the appended claims, reference being had to the accompanying drawings forming a part of this specification, and in which:—

Figure 1 is a view partly in side elevation and partly in section showing the lower portion of a tool embodying the present invention,

Figure 1^a is a similar view of the upper portion of the tool shown in Figure 1,

Figure 2 is a plan view of the lower end of the tool,

Figure 3 is a view in transverse vertical section of the lower portion of the tool,

Figure 4 is a detail perspective view of one of the drilling cutters,

Figure 5 is a fragmentary sectional detail taken on the line 5—5 of Figure 2, and

Figure 6 is a similar sectional detail taken on the line 6—6 of Figure 2.

Referring to the drawings it will be seen that the tool comprises a one piece tubular body 1 having a plurality, preferably three, longitudinally extending and outwardly projecting ribs 2. At the lower ends of the body slots 3 are formed therein and in the ribs 2 and these slots extend transversely of the body and are smaller at their lower than at their upper ends, these slots tapering or gradually decreasing in size from their upper to their lower ends. In the slots 3 the correspondingly tapered attaching portions 4 of the drilling cutters 5 are mounted. The cutters 5 are held in position in the slots 3 by

virtue of the tapered form of the slots and the corresponding tapered form of the attaching portions 4 of the cutters and by virtue of the securing action of a cylindrical coring member 6, the cylindrical coring member 6 having a reduced and externally threaded upper end 7 threadedly engaged with the tubular body 1 and abutting the inner ends of the attaching portions 4 of the cutters to hold the cutters 5 in position. The lower end of the coring member 6 is provided with cutting teeth 8.

The upper end of the tubular body 1 is provided with a reduced externally threaded extension 10 threadedly connected or otherwise suitably secured to the lower face of the drill pipe 12.

The coring member 6 has its longitudinal opening 11 tapering gradually from a small lower end of a large upper end and this formation of the coring member tends to retain the core in the member and in the core barrel 12 which the longitudinal bore of the tubular body 1 provides. At the upper end of the tubular body 1 a tubular core barrel extension 15 is provided, the core barrel extension being of any suitable length but preferably being of substantial length. The lower end of this core barrel 15 is threadedly connected with the upper end of the tubular body 1 and beyond its threaded connection with the tubular body 1 this extension 15 is located within the drill stem. At its upper end the extension 15 is provided with a valve seat 16 with which a ball valve 17 co-acts. A cage 18 is provided for the ball valve. The ball valve 17 controls the communication of the interior of the extension 15 with the interior of the drill stem. As the extension 15 is smaller in diameter than the drill stem a space 20 is provided between the outside of the extension 15 and the inside of the drill stem and through this space 20 the circulating fluid is pumped. From the space 20 the fluid passes

through longitudinal openings 21 formed in the stock or material of the tubular body 1. These openings 21 extend all the way down through the body 1 and their lower ends discharge below the body and adjacent longitudinally extending slots 22 formed at the

outer surface of the coring member 6 so that the circulating fluid not only courses around the cutters 5 but also travels down to and courses around the cutting teeth 8. The passage of the fluid through the slots 23 decreases the resistance which the formation sets up to the rotation of the coring member 6.

In operation the cutters 5 serve to carry out the drilling of the well and simultaneously with their operation the teeth 8 cut a core from the formation and the core so cut passes up through the coring member 6 and into the barrel 12. The tapered formation of the coring member 6 tends to retain the core in position and this function is enhanced by the section of the valve 16 which permits displacement of fluid out of the core barrel and which automatically closes to prevent escape of the core.

We claim:—

1. A core bit comprising a tubular body, radially offset ribs spaced about the outer side of said body, said ribs having slots opening inwardly of the same and into the bore of said body, cutters disposed beneath said ribs and having portions engaged in the said slots, and a cylindrical core cutter seated in the lower end of the bore of said body and abutting the inner sides of the engaged portions of said cutters to lock the latter in position.

2. A core bit comprising a tubular body, radially offset ribs at the outer side of said body and having their lower ends disposed substantially in the plane of the lower end of the latter, said ribs having slots opening inwardly of the same and into the bore of said body, cutters disposed beneath said ribs and having reduced portions formed therewith to be engaged in the said slots, a shoulder formed at the outer side of each of said cutters and engageable with the lower end of the complementary of said ribs, and a cylindrical core cutter seated in the lower end of the bore of said body and abutting the inner sides of the engaged portions of said cutters to lock the latter in position.

3. A core bit comprising a tubular body, radially offset vertical ribs spaced circumferentially about the outer side of said body and having their lower ends projecting slightly below the lower end of the latter, said ribs having slots opening outwardly of the lower ends of the same and into said body, cutters disposed beneath said shoulders and having portions engaged in the said slots, said slots being tapered in a downward direction for interlocked engagement with the engaged portions of said cutters, and a cylindrical core cutter seated in the lower end of the bore of said body and abutting the inner sides of the engaged portions of said cutters to lock the latter in position.

4. A core bit comprising a tubular body,

radially offset vertically elongated ribs spaced circumferentially about the outer side of said body and having their lower ends projecting slightly below the lower end of the latter, said ribs having slots opening outwardly of the lower ends of the same and into said body, cutters disposed beneath said shoulders and having portions engaged in the said slots, said slots being tapered in a downward direction for interlocked engagement with the engaged portions of said cutters, a cylindrical core cutter seated in the lower end of the bore of said body and abutting the inner sides of the engaged portions of said cutters to lock the latter in position, and water courses passing downwardly of said body in planes between the said ribs and adjacent the leading edges of said cutters.
